United States Patent Office

Des. 176,958
Patented Feb. 21, 1956

176,958

FLASHLIGHT

Edward C. Klotz, Jr., Milwaukee, Wis., assignor to Ray-O-Vac Company, Madison, Wis., a corporation of Wisconsin

Application June 29, 1954, Serial No. 31,222

Term of patent 14 years

(Cl. D48—24)

Fig. 1

Fig. 2

I claim:

The ornamental design for a flashlight, as shown.
